CLAIM

The ornamental design for a case for mobile phone, as shown and described.

DESCRIPTION

FIG. 1 is a front, right and top perspective view of a case for mobile phone according to a first embodiment of our new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof, showing a ring of the case for mobile phone in a first open state;

FIG. 10 is another front perspective view thereof, showing the ring of the case for mobile phone in a second open state;

FIG. 11 is a front, right and top perspective view of a case for mobile phone according to a second embodiment of our new design;

FIG. 12 is a rear, right and top perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a front perspective view thereof, showing a ring of the case for mobile phone in a first open state; and,

FIG. 20 is another front perspective view thereof, showing the ring of the case for mobile phone in a second open state.
